US0D1076926S

(12) **United States Design Patent** (10) Patent No.: **US D1,076,926 S**
(45) Date of Patent: ** May 27, 2025

(54) **STAND FOR ELECTRONIC EQUIPMENT**

(71) Applicant: **Yuta Yoneyama**, Kawasaki (JP)

(72) Inventor: **Yuta Yoneyama**, Kawasaki (JP)

(**) Term: **15 Years**

(21) Appl. No.: **35/521,229**

(22) Filed: **Jun. 8, 2023**

(80) **Hague Agreement Data**

Int. Filing Date: **Jun. 8, 2023**

Int. Reg. No.: **DM/229596**

Int. Reg. Date: **Jun. 8, 2023**

Int. Reg. Pub. Date: **Jun. 14, 2024**

(30) **Foreign Application Priority Data**

May 15, 2023 (JP) ..... 2023-009790 D

CLAIM

The ornamental design for a stand for electronic equipment, as shown and described.

DESCRIPTION

1. Stand for electronic equipment

1.1 : Front

1.2 : Back

1.3 : Right

1.4 : Top

1.5 : Bottom

1.6 : Perspective

Thin lines shown in the drawings are intended to represent the three-dimensional contour of the design, and are not

(Continued)

intended to indicate surface decoration; the left view is omitted because it is symmetrical with the right view.

1 Claim, 6 Drawing Sheets
